JAW PLATE FOR JAW CRUSHERS

Alexander J. Roubal, Milwaukee, Wis., assignor to Allis-Chalmers Manufacturing Company, Milwaukee, Wis.

Application July 8, 1952, Serial No. 297,596

4 Claims. (Cl. 241—291)

This invention relates to an improvement in jaw plates of the kind utilized for the movable and stationary jaws of jaw crushers.

Jaw plates are customarily made of hard, tough steel, such as manganese steel, which in operation may become deformed by repeated impacts of the rock or other material being crushed. The metal at the working surface of the plate is peened by the impacting of the material being crushed in such a manner that the surface layer tends to expand laterally by cold working action. Lateral expansion of the working surface in prior art jaw plates causes the plates to warp in that the metal at the rear surface of the plate, which is not subjected to a peening action, does not expand laterally. This expansion of the working surface, without corresponding expansion of the rear surface, causes a deformation or warping of the jaw plate such that the working surface of the plate bows outwardly and the rear surface of the plate becomes a concave surface. In becoming a concave surface, the center portion of the rear surface pulls away from the flat seat of the jaw against which it is meant to be secured.

Warping of the jaw plate in this manner puts a severe strain on the fastening bolts, frequently stretching them permanently, and the jaw plate becomes deformed until only its vertical edges are in contact with the flat jaw seat such that the middle portion of the plate is unevenly or incompletely backed. When the jaw plate is supported only along its edges it is equivalent to a beam supported only at its ends and, as a crushing force is applied to the plate each time the jaws move together, the jaw plate is subjected to repeated bending stresses which tend to cause the plate to crack due to fatigue failure. In one instance known to the present inventor fatigue failure of this nature caused the development of a crack eighteen inches long and one and three-quarters inches wide.

An object of the present invention is to provide a new and improved jaw plate which will not warp, bow or be appreciably deformed by repeated impacts against its working surface of the material being crushed.

A more specific object of the invention is to provide the working surface of a jaw plate with recesses into which cold worked metal of the working surface may flow to prevent overall lateral expansion of the working surface.

The above and other objects and advantages appearing herein may be carried into practical effect in the manner described hereinbelow, reference being made to the accompanying drawing in which:

Fig. 1 is a cross sectional view taken through a jaw crusher having jaw plates of the type in which the present invention may be embodied;

Fig. 2 is a broken sectional view of one of the jaw plates of Fig. 1, constructed in accordance with the present invention; and

Fig. 3 is a sectional view of a typical jaw plate that does not embody the present invention. Superimposed

2

thereon, in dotted lines, is the shape (exaggerated for the sake of illustration) the plate will assume after its working action referred to hereinabove.

The crusher illustrated in Fig. 1 is an ordinary jaw type crusher having a stationary and a movable jaw each equipped with jaw plates of the type in which the present invention may be embodied. The frame 1 of the crusher has a stationary jaw body 2. A movable or swinging jaw body 3 is pivoted to frame 1 at 4 and has a crushing movement imparted to it by a crusher toggle 6 actuated by a mechanism well known in the art and forming no part of the present invention.

Stationary jaw body 2 and swing jaw body 3 each have two jaw plate receiving surfaces or seats 7 which may or may not be formed on renewable backing plates 8. Fastened on jaw bodies 2 and 3 are a plurality of heavy steel jaw plates 9 formed with their rear surfaces adapted to fit against suitably formed seats 7. Intermediate the corners of each of the jaw plates 9 are formed one or 20 more counterbore recesses for receiving the heads of bolts 11, the shanks of which pass through holes in jaw plates 9 and respectively through holes in the jaw bodies 2 and 3.

The foregoing structure is well known and forms no 25 part of the present invention.

With reference to Fig. 2, the present invention pertains to the providing of working surface 15 of a jaw plate 9 with longitudinally extending re-entrant recesses or grooves 16 into which cold worked metal of surface 15 may flow to prevent an overall lateral expansion of the working surface. Working surface 15, as seen in section in Fig. 2, appears as a series of waves with the projections or crests 17 of each of the waves extending longitudinally of the jaw plate 9. Juxtaposed crests 17 are valley portions which provide working surface 15 with a cross sectional appearance similar to a conventional sign wave curve. A valley portion, therefore, comprises a descending or negative slope segment, an ascending or positive slope segment, and a bottom segment. The bottom segment corresponds analogously to the peak of the negative half cycle of the sign wave curve. One or more re-entrant recesses 16 are formed in each of the valley portions of the working surface 15 between crests 17, e. g., in Fig. 2 two re-entrant recesses 16, 16 are disposed in a valley portion, one on the ascending slope segment and one on the descending slope segment. Thus the working surface 15 is interrupted by the gaps defined by recesses 16, 16. Recesses 16 as seen in Fig. 2, are defined in part by opposed spaced sidewall portions which extend generally normal to and merge with working surface 15. When the surface layer of each portion of working surface 15 expands laterally due to cold working, the surface layer of metal flows so as to cause recesses 16 to close but an overall lateral expansion 50 of working surface 15 does not occur.

It is seen that by preventing an overall expansion of working surface 15, the normal tendency of the jaw plate 9 to bow or become warped is eliminated. The rear surface 18 of the jaw plate therefore remains flat instead 55 of assuming a concave shape as when the plate becomes bowed. As a metal surface can be cold worked to the point where further impacting produces no appreciable expansion in the surface, the dimensions of grooves 16 may be predetermined such that no further expansion of the working surface, or portions thereof, will occur after the grooves are closed.

The advantage of applicant's invention in preventing an overall expansion of working surface 15 will be more fully understood from a discussion of how a jaw plate 70 normally responds to cold working of its working surface. Fig. 3 shows a typical jaw plate in section which

does not embody the grooves of the present invention. Superimposed in dotted lines on the jaw plate in Fig. 3 is the shape, shown exaggerated for the sake of illustration, the plate will assume after its working surface is cold worked by the crushing impacts to which jaw plates are normally subjected.

It is well known that in the operation of a corrugated wear plate, the greatest wear occurs at the ridges or crests, less wear occurs at the bottom segments of the valley portions, and the least wear occurs at the slope segments.

Cold working of working surface 115 causes it to expand laterally in both directions from line 120 (Fig. 3) and, as the actual length of rear surface 118 is not lengthened correspondingly, the jaw plate becomes bowed such that rear surface 118 becomes a concave surface as indicated by broken line 118' and working surface 115 bows outwardly as indicated by broken line 115'. The undesirability of having the jaw plate bow outwardly in this manner is that the plate is supported only along its edges leaving the middle portion of the plate unevenly or incompletely backed. The plate will tend to flatten out each time the jaws of the crusher move together and the intermittent bending stresses will ultimately cause the plate to crack due to fatigue failure.

Lateral expansion of the working surface 15 as described above also causes plates 9 to expand laterally, as indicated in Fig. 3, such that the plates may ultimately contact the stationary sidewalls of the crushing chamber. Thus, when one of the plates 9 on movable jaw 3 contacts the sidewalls in this manner, the swinging action of the jaw meets with continually increasing resistance and finally stops when such resistance becomes too great to be overcome.

It will be understood the particular embodiment of the invention described herein and illustrated in the drawing is exemplary only, and the invention as applied to jaw plates for crushers is intended to include such modifications and equivalents as may readily occur to persons skilled in the art, the invention being limited only by the terms of the appended claims.

It is claimed and desired to secure by Letters Patent:

1. A wear plate for the working surface of a machine for crushing material, said wear plate presenting a working surface having a plurality of juxtapositioned valleys and ridges extending in the direction of the flow of said material when said plate is in working position, a portion of said working surface which includes adjacent ridge and valley surface areas being provided with an elongated recess which also extends in said direction of

flow of material, said recess being defined in part by spaced opposed sidewall portions which are disposed generally normal to and merge with said ridge and valley surface areas of said portion of said working surface.

2. A wear plate for the working part of a machine for crushing material, said wear plate presenting a working surface having a plurality of juxtapositioned valleys and ridges extending in the direction of the flow of said material when said plate is in working position, said working face having adjoining ridge and valley portions thereof provided with an elongated recess which also extends in said direction of flow of material, said recess being defined in part by spaced opposed sidewall portions which are disposed generally normal to and merge with said ridge and valley portions of said working surface.

3. A wear plate for the working part of a machine for crushing material, said wear plate presenting a working surface having a plurality of juxtapositioned valleys and ridges, said valleys and ridges extending in the direction of the flow of said material when said plate is in working position, said wear plate further presenting a re-entrant recess defined in part by spaced opposed sidewall portions extending generally normal to said working surface, said recess extending parallel of said ridges intermediate one of said ridges and the valley adjacent thereto.

4. A wear plate for the working part of a machine for crushing material, said wear plate presenting a working surface having a plurality of juxtapositioned valleys and ridges, said valleys and ridges extending in the direction of the flow of said material when said plate is in working position, said wear plate further presenting a plurality of re-entrant recesses, each of said recesses being defined in part by spaced opposed sidewall portions extending generally normal to and merging with said working surface and extending parallel to said ridges intermediate one of said ridges and the valley adjacent thereto.
